(57) **CLAIM**

The ornamental design for a depth of field adapter, as shown and described.

DESCRIPTION

FIG. 1 is a top perspective view of a depth of field adapter; FIG. 2 is a bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken line showing of a top mount, an adjustment knob, bayonet holder mounts, and threading are included for the purpose of illustrating environmental structure and forms no part of the claimed design.
